UNITED STATES PATENT OFFICE.

FRED W. NOLTE, OF ST. LOUIS, MISSOURI.

SELF-ADJUSTING EYEGLASS-FRAME.

SPECIFICATION forming part of Letters Patent No. 407,789, dated July 30, 1889.

Application filed July 17, 1888. Serial No. 280,162. (Model.)

To all whom it may concern:

Be it known that I, FRED W. NOLTE, of the city of St. Louis, in the State of Missouri, have invented a certain new and useful Improvement 5 in Self-Adjusting Eyeglass-Frames, of which the following is a full, clear, and exact description, reference being had to the accompanying drawings, forming part of this specification.

10 This invention relates to devices for an eyeglass-frame with a bridge-connection and self-adjusting pivotal spring nose-pieces; and the invention consists in features of novelty hereinafter fully described, and pointed out 15 in the claims.

Figure I is a front view of my eyeglass-frame and shows the bridge and nose pieces in position. Fig. II is a back view of the same and shows the means of attachment of 20 the bridge and of the pivotal spring nose-pieces, the latter in their contracted position previous to seating on the nose of the wearer. Fig. III is a like view showing the nose-pieces expanded apart ready for placing on the 25 nose. Fig. IV is an enlarged horizontal section taken on line IV IV, Fig. II, and shows the bridge and spring attachment. Fig. V is an enlarged inclined section taken on line V V, Fig. II, and shows the pivoted clip that 30 holds the spring-frame of the nose-pieces, and on which said spring-frame fulcrums. Fig. VI is a horizontal section, taken on line VI VI, Fig. IV, with part broken away, and shows the spring nose-pieces embracing the angle- 35 pin of the bridge and its loose end backed against the inner course of the bifurcated strap that couples the bridge and nose pieces. Fig. VII is an enlarged perspective disconnected view of some of the novel associate 40 parts used in the construction of my self-adjusting eyeglass-frame and shows the bridge, the spring nose-piece, the clip for the attachment of said nose-piece to the frame, and the bifurcated strap hereinafter described.

45 Referring to the drawings, in which similar figures of reference indicate like parts in all the views, 1 represents the individual glass-frames, which may have the usual inner channel-groove for embracing the glass, or made 50 of round wire for embracing grooved lenses. Screw-lugs 2 tighten the glasses when secured

by screws 3, and a loop 4 forms the handle, which, however, may be made in any other convenient shape.

5 represents the bifurcated rectangular 55 loop-straps, which are relatively rigidly secured on the inside of the glass-frames, presenting toward each other. These straps are provided with holes 6, in which the longitudinal stems 7 of the bridge-piece 8 work, while 60 the angle-pins 9, that project inward from said stems, engage within the slots 10, which are formed by the forks 11 of the bifurcated straps 5, and said pins move back and forth within the slot 10 as said glass-frames 1 are 65 moved toward and from each other.

12 represents the spring-frames that constitute the nose-pieces, (for the retention of the eyeglasses in their operative position,) the closed loops 13 on the fast ends of which embrace 70 the angle-pins 9, and the curvilinear semi-loops 14 at the loose ends of which press against the inner surface of the rectangular bifurcated loop-straps 5, the frame constituting a reactionary loop-spring. 75

15 represents clips that embrace the spring-frame of the nose-pieces near the middle of their rear attached sides, and said clips are secured to the frames of the glasses by screws 16, which pass through the perforated lugs 17 80 of the clips and screw into the lugs 18, that project from the glass-frames.

19 are the cushions of the nose-pieces, which may be made of cork, rubber, or any other suitable substance, and they are secured to 85 the spring-frame by rivets 20, or by other suitable means, on its loose side, to provide a soft elastic cushion for contact with the nose.

The great difficulty hitherto experienced of the construction and coupling of eyeglasses 90 by a similar bridge to that used in the construction of spectacles is overcome in this invention by means of the self-adjusting glass-frames which slide to and from the bridge on the stems 7 and pins or pivots 9, and the self-adjusting pivoted and fulcrum-spring nose-pieces. All kinds of bridges—such as snake, saddle, band, arch, C, K, X, &c., as best adapted for the use of the wearer—are (unlike with the common eyeglasses) well suited for this 95 invention. 100

It will be seen that when the glass-frames

1 are drawn apart the angle-pins of the bridge slide in their slotted seats, and constitute at the same time stationary pivots that hold the fast loop ends of the spring of the nose-pieces, 5 while each of the free ends of said springs are carried by the inner bends of the straps 5 toward its respective fast end or the pivot 9, thereby fulcruming said springs on their attachment-clips 15 and expanding and contracting their lower portions (with the cushions they carry) at an increased ratio to that above, thus conforming to the requirements 10 of the nose of the wearer and to the alternating expansion and contraction of the nostrils 15 in breathing. It will also be seen that the curve of the bridge always retains its central position, for the expansion is evenly effected on either side, so that the curved seat rides the nose without frictional movement, and 20 consequently will not gall the same or throw the glasses out of position. The nose-pieces are not only self-adjusting, but they, as well as the bridge, are easily detachable and interchangeable for others of a different shape, 25 &c., by the withdrawal of the single screws that secure the clip attachments. The loop attachment of the spring-frame of the nose-piece around the pin 9 that angles from the bridge-stem, and also its loose end, keep the 30 plane of the lenses out of divergence from the straight or true line during the going and coming movement of the frames 1 and nose-pieces.

In fact, it will be seen that the self-adjusting and adjustable movements of the various 35 coacting parts, while they admit of a free and easy movement in the desired expansion and contraction of the parts, also prevent the tilting of the lenses out of position or into an 40 adverse angle to the line of vision.

The bifurcated loop-straps, in which the angle-pin of the bridge travels, in conjunction with the aforesaid action of the spring-loops of the nose-pieces, enforce the retention in position 45 of the lenses when on the nose of the wearer. The eyeglass is thus made to set perfectly straight before the eyes of the wearer, which is essential to all persons wearing cylindrical lenses, as such lenses are used 50 to correct an error of refraction of the eye, called "astigmatism." The axis of the lenses must therefore set at a certain angle before the eyes.

It will be seen that my loop-spring nose-pieces provide facilities for opticians to 55 change the set of the nose-pieces by a change in the curves of the spring-loops to accommodate the wearer; also, by the withdrawal of the attachment-screw, more or less prominent 60 nose-pieces may be made to replace those that do not constitute a good fit. The nose-frames and bridge can also be readily adjusted either to a higher or lower pitch, either for distance or reading and writing glasses.

65 The nose-piece is adjustable to any-shaped nose. For instance, should the nose be thicker where coming in contact with the bottom of

the nose-piece, the optician bends the nose-pieces back to fit the nose and to allow the eyeglass to close up. If, on the contrary, it 70 is thicker at the top, the nose-piece will give way, as it hangs loose within the bifurcated strap-loop.

The springs in my eyeglasses act direct on the sides of the nose, instead of other spring-frames that act only from above, and cannot, therefore, (as are these,) be as efficiently under control, and by the said side (instead of top) adjustment and the nose-pieces being set back of the plane of the lenses said lenses 80 are thrown farther forward out of interference with the lashes of the eyes; also, the said side grip of the nose-pieces, with their pivotal fulcrum attachment, provides a more secure hold for the glasses with more ease to 85 the wearer.

By combining side loop-springs with the nose-pieces I obviate the necessity of spiral, arch, or any form of surmounting spring, that is both liable to get out of repair and injuriously presses down on the nose, instead of, as does the present invention, on its side, and loop-springs being used the tension is 90 held for a much longer time than it could be with spiral springs.

As the bridge and nose pieces are detachable and interchangeable, opticians can, after the removal of the single screws that secure the fulcrum-clip, change the parts, a larger, deeper, shallower, or other style of bridge being 95 easily attached; also a longer, shorter, broader, or narrower nose-piece. The eccentric movements of the sliding bridge, the spring-bearing traveling pivot-pin it carries, with the attachment-clip on which said spring fulcrums 100 to effect, in an increased ratio, the relative 105 lower expansion of the nose-cushions, all coact to accommodate the seating of the eyeglasses, and are conducive to the ease and convenience of the wearer.

When the nose of the wearer is heavy at top, the springs press outward and present the nose-pieces and their cushions in the position shown in broken lines in Fig. I.

I claim as my invention—

1. In eyeglasses, the bridge having connecting-stems, and the sliding bifurcated loop-straps, within which the connecting-stems of said bridge fit, substantially as and for the purpose set forth.

2. In eyeglasses, the combination of the bridge having connecting-stems, the bifurcated loop-straps, within which loops the connecting-stems of said bridge fit, the angle-pins projecting inward from said stems into the bifurcations of said loop-straps, and the reactionary loop-spring nose-pieces, whose fast ends are secured to said angle-pin, and whose loose ends spring against and within said loop-straps, substantially as and for the purpose 130 set forth.

3. In eyeglasses, the combination of the bridge having connecting-stems, the bifurcated loop-straps, within which the connect-

ing-stems of said bridge fit, the traveling angle-pin at the terminals of said stems of the bridge projecting into said bifurcations, the reactionary loop-spring frames constituting 5 the nose-pieces, the said frames pivotally looped around said angle-pins, the loose end of said spring-loop pressing against and within said loop-strap, the clips 15, embracing the spring-loops near the middle of their attached

10 sides, and the screw attachments by which said clips are secured to lugs that project from the eyeglass-frames, the said clips providing a fulcrum attachment to secure the relatively-increased expansion and contraction of the 15 lower part of the nose-pieces, substantially as and for the purpose set forth.

4. In eyeglasses, the combination of the frames 1, the spring-loop nose-pieces, the loop-20 straps secured to said frames and having bifurcations, the bridge-piece having connect-

ing-stems and angle-pins projecting from said stems and fitting in said bifurcations, and the fulcrum-clips securing the said spring-loop nose-pieces to the frames, whereby said spring-loop fulcrumed on the clip secures an increased ratio of expansion and contraction relatively in the movement of the lower portion of the nose-pieces, substantially as set forth. 25

5. In eyeglasses, the combination, with the 30 glass-frames, of the loop-straps 5, a bridge having stems fitting in said loop-straps, and the spring-loops carrying nose-cushions having their ends secured to said stems and bearing against said loop-straps, as set forth.

FRED W. NOLTE.
